 tion of Pennsylvania

Application March 20, 1948, Serial No. 16,011

13 Claims. (Cl. 315—3)

1

The present invention relates generally to the electromagnetic traveling wave tube art, and more particularly to novel apparatus based upon the principles of beam traveling wave electron tubes and adapted to produce high intensity, high velocity beams of charged particles.

This application is a continuation-in-part of my co-pending patent application Serial No. 761,798, filed July 18, 1947, which issued as Patent No. 2,541,843 on February 13, 1951. For information purposes, reference is made to my co-pending patent applications Serial No. 788,724, filed November 28, 1947, and Serial No. 4,849, filed January 28, 1948, which issued as Patent No. 2,584,308 on February 5, 1952. The latter two applications are also continuations-in-part of the aforesaid parent application Serial No. 761,798.

Beams of high velocity, high energy electrostatically charged particles have extensive application in the physical arts. The conventional type cathode ray tube is an example of a common use of a high energy electron beam. For use in connection with nuclear studies, special beam generating apparatus has been developed, including such particle generators as the cyclotron and the synchrotron.

It is well known in the art that a charged particle, such as the electron, may be accelerated to an extremely high velocity and consequently high energy level by allowing the electron freely to traverse a path within a high voltage electric field. For particle velocities approximately one tenth that of the velocity of light or less, the final velocity of the electron is proportional to the square root of the accelerating potential. It has been generally recognized that the generation of particle beams solely through the use of high potential accelerating fields is impractical when it is desired to obtain extremely high energy particles. The application of a potential between 50,000 volts and 1,000,000 volts involves numerous special electrical design considerations and presents a distinct hazard to operating personnel. Extremely high voltage cathode ray tubes, as required for large television images of considerable brightness, are particularly hazardous since these high voltages must be present in the home, where serious harm may be caused by failure to incorporate reliable safety apparatus.

Modern particle accelerators such as the cyclotron and others obtain high energy particles by imparting to these particles a considerable number of cumulative accelerating impulses, and thereby successively raise the total particle energy to the desired level. However, a cyclotron or like machine is wholly impractical outside the

2

laboratory, principally because of its huge size and cost.

A recent electronic development, known as the beam traveling wave tube is utilized, in accordance with the principles of the present invention, to provide means for obtaining high energy charged particle beams. Because of the simplified nature of the present apparatus, it may be incorporated into conventional electronic equipment requiring particle beams.

For a general description and illustration of the development of the beam traveling wave tube, reference is made to the publication "Bell Laboratories Record" of December 1946, and to the article therein, entitled "The Beam Traveling Wave Tube" by J. R. Pierce. In this reference the traveling wave tube is described as constituted of an electron gun similar to those employed in cathode ray tubes. An electron beam generated by the gun is directed along the axis of a long evacuated tube and impinged upon a collector anode. Within the tube, and surrounding the beam axis, is a closely wound wire helix which is excited at the electron gun end thereof by the weak signal to be amplified and which provides at the collector end thereof the amplified output signal. The tube contains no signal grids in the conventional sense.

Broadly speaking, the applied signal travels along the wire helix as an electromagnetic wave at a speed approaching the speed of light. As is determined by the pitch of the helix, the wave travels axially of the tube at a fraction of the speed of light; and the electron gun and collector anode potentials are arranged so that the average axial velocity of the electron beam through the helix is somewhat greater than the axial wave velocity.

Interaction of the electron beam and electromagnetic field components extending from the helix produces signal amplification. The greater the electron current and the longer the helix, the greater is the gain. In transit through the helix, the average electron velocity is reduced, and the diminution of energy represented by this decreased velocity is imparted to the signal. The tube does not require a tuned circuit in the signal path, the wire helix being in effect an all-pass transmission line. Hence the tube is capable of operation over an exceedingly wide frequency range. In practice this range is limited somewhat by the impedance match of the helix to the external circuits.

In operation the signal appearing on the helix acts on the electron stream and gradually produces fluctuations in velocity and density. The

density modulated electron beam delivers energy to the wave and over the helix section nearest the collector there is a substantially uniform gain per unit length of travel.

In my aforementioned co-pending patent applications there are described numerous embodiments of beam electromagnetic traveling wave tubes having application as broad band microwave amplifiers, oscillators, frequency converters or mixers and the like. The electron tubes disclosed in these above identified patent applications utilize wave guides for directing wave signals around the path of an electron beam. These guides permit direct coupling of the electromagnetic fields therein and the tube electron beam and have the advantage of precluding excessive energy radiation and undesirable coupling with external fields.

In the aforementioned patent applications it was demonstrated that signal amplification could be obtained in an electromagnetic traveling wave tube by causing an electron beam to traverse the axis of first and second, or input and output, helical wave guide sections of predetermined pitch and number of turns. The input wave guide was energized by the weak incoming signal, whereby the electron beam was bunched or density modulated. The modulated beam was then caused to traverse a second or output helical wave guide section and to deliver energy thereto to provide the amplified output signal.

In a tube of this construction, input and output wave guides are spaced axially of the electron beam. When certain conditions of beam velocity and helix structure are properly satisfied, considerable gain is obtained and the electron tubes are capable of either amplifier or oscillator operation; the latter being accomplished by coupling a predetermined portion of the output signal in the correct phase to the input wave guide. For traveling wave tubes having independent input and output wave guide sections, it has been determined that the optimum average beam velocity through the guides is equal to the axial component of velocity of the electromagnetic traveling wave.

It has also been demonstrated in the aforementioned patent applications that a single helical wave guide could be utilized for both modulating and extracting energy from an electron beam, such that an incoming signal could be coupled into the wave guide at the input or electron gun end thereof and the amplified output signal could be derived from the opposite end thereof. For single wave guide operation, it was demonstrated that optimum electron beam velocity was somewhat higher than the axial velocity component of the traveling wave in the tube. In transit through the tube, each group of electrons was shown to deliver energy to the traveling wave, and the consequence thereof, the output signal, was at a level considerably above that introduced at the input end of the guide.

It has been observed and clearly described in the above-mentioned co-pending patent applications that in transit through the beam traveling wave tube, the electron beam tends to become bunched in the positive potential regions of the traveling wave. In the traveling wave tube utilizing a single helical wave guide for amplification or signal generation and utilizing a beam velocity somewhat higher than the traveling wave axial velocity, this bunching effect results

in a general retardation of electrons in the beam. Physically, this retardation or general lowering of the average electron velocity in the beam is a consequence of the transfer of energy from the electron beam to the traveling electromagnetic wave. It is, in fact, this energy transfer from beam to wave which results in signal amplification such that the output traveling wave is at an energy level considerably above the input traveling wave.

If electrons were to enter the region of coupling with the electromagnetic traveling wave at an axial velocity somewhat less than the axial velocity of the traveling wave, then this bunching effect, which tends to synchronize the axial flow of electrons with the axial movement of positive potential regions of the traveling wave, would result in a general increase of average electron velocity. Obviously, this velocity increase which represents an increase in overall beam energy level is effected by the extraction of energy from the traveling wave. For this reason, it was stated in co-pending application Serial No. 761,798 that electron velocities below the axial velocity of the traveling wave were undesirable since signal amplification could not be thus accomplished.

It is broadly an object of the present invention to provide means for utilizing the hereinabove mentioned principles of beam traveling wave tube operation for obtaining high intensity and high velocity charged particle beams readily adaptable for laboratory purposes and to inexpensive and non-hazardous commercial equipment. In its basic form the apparatus of this invention comprises an electron beam generator of a conveniently obtainable low energy level and associated means for providing an axially moving electromagnetic traveling wave arranged for interaction with the electron beam. At its input end the axial velocity component of the traveling wave is substantially equal to the axial velocity of the generated electron beam. However, means are provided for gradually and uniformly increasing the axial velocity component of the traveling wave which correspondingly increases the average axial velocity of the electron beam at the expense of energy transferred from the traveling wave to the electron beam. There is thus produced an electron beam having an average velocity greater than that originally imparted thereto by the electron beam generating means.

The electromagnetic traveling wave having the necessary axial velocity component is obtained by suitably energizing a helical wave guide of the type completely described in the aforementioned co-pending patent applications. Gradual increase in axial velocity of this traveling wave while traversing its path is effected by forming the helical guide with uniformly increasing pitch in the direction of wave travel.

It is accordingly an object of the present invention to provide novel means for generating high intensity beams of electrostatically charged particles.

Another object of the present invention is to provide means incorporating guides for electromagnetic traveling waves for accelerating particles in a charged beam.

A further object of the present invention is to provide means for gradually increasing the axial component of velocity of a helically traveling electromagnetic wave.

Still another object of the present invention is

to provide means for accelerating electrons within a beam to velocities far in excess of those imparted by electrostatic fields in the beam generating means.

Another object of the present invention is to provide an electron beam accelerator utilizing a helical wave guide structure excited by a high frequency electromagnetic wave.

A further object of the present invention is to provide a novel cathode ray tube utilizing a helical wave guide electron beam accelerator for obtaining high beam intensity without the requirement of externally generated and applied high direct voltage.

These and other objects of the present invention will now become apparent from the following detailed specification when taken in connection with the accompanying drawings in which:

Figure 1 is an axial sectional view of a particle accelerator incorporating the principles of the present invention, and

Figure 2 is a sectional view of a cathode ray tube having beam accelerating means utilizing the novel particle accelerator illustrated in Figure 1.

With reference now to the drawings and more particularly to Figure 1 thereof, there is illustrated an electron beam accelerator tube incorporating the features of the present invention, and comprising generally a comparatively large diameter, evacuated glass, or other dielectric cylinder 11, having tapered ends 12 and 13.

Sealed into the left end 12 of the glass cylinder 11, are the electrodes of an electron gun 20 similar to those utilized in conventional cathode ray tube structures. As shown, the electron gun 20 comprises a heater 22 and its associated cathode 23, a centrally perforated control grid 24 and focusing and accelerating hollow cylindrical electrodes 25 and 26, respectively. When the electrodes comprising the electron gun 20 are energized from power source 19 an axial beam of electrons of predetermined velocity is generated and directed along the axis 28 of cylinder 11 toward a disc shaped collector electrode 27 sealed into the right-hand end 13 of the tube, as viewed in Figure 1.

As is well understood in the electron gun art, the velocity of electrons leaving the accelerating electrode 26 is on the average substantially proportional to the square root of the potential difference between the cathode 23 and the accelerating electrode 26. As discussed hereinabove, this square root relationship between velocity and potential difference seriously limits the ability of conventional electron accelerating devices to provide extremely high velocity electrons without the use of impractically high voltages. In the present apparatus it will be understood that the electron gun 20 is of the type used in a conventional low-voltage cathode ray tube and consequently, does not by itself produce extremely high velocity electrons, nor require excessive hazardous voltages requiring particularly reliable safety enclosures and expensive and weighty insulation.

Structural means required for supporting the electron gun electrodes have been omitted from the drawing for clarity. Further description of the energizing means 19 are considered unnecessary at this point, since electron beam generators or electron guns of the type illustrated are sufficiently well-known in the electronic art.

In accordance with the broad principles of the present invention, the axial path of travel of the

5 electron beam between the electron gun accelerating electrode 26 and the collector electrode 27 is substantially enclosed within a helical wave guide assembly, a portion of which, as will be described below, serves to increase considerably the average velocity and energy level of the electron beam prior to its contact with collector electrode 27.

As illustrated in the drawing, the region within glass cylinder 11 between accelerating electrode 26 and collector anode 27 is enclosed by a conductive metallic cylinder 31, having an axis substantially coincident with the electron beam path 28 and lying in surface contacting relationship with the inner wall of glass cylinder 11. The space within metallic cylinder 31 is divided axially into two regions, the left portion 32 comprising a high frequency oscillator or exciter and the right portion 33 comprising an electron accelerator.

20 The exciter section 32 of the apparatus illustrated in Figure 1 comprises basically a beam traveling wave oscillator operating on the principles described in considerable detail in the aforementioned application Serial No. 788,724. This oscillator, as illustrated in Figure 1, is constituted of a single helical wave guide 41, formed of a thin, highly conductive metallic strip 42, helically wound in edgewise contacting relationship with the hollow cylindrical conductive enclosing cylinder 31. It will be noted that the helical wave guide 41 is of substantially uniform pitch.

25 The radial dimension of the conductive strip 42, as illustrated in Figure 1, is somewhat less than the inner radius of the conductive cylinder 31 and accordingly, the inner edge 43 of the conductive strip 42 forms a helix lying in a cylindrical surface enclosing the axis 28 of electron travel.

30 The wave guide 41 defined by helically wound strip 42 and its enclosing conductive cylinder 31 is a helical passage of substantially uniform rectangular cross-section, and which progresses axially of the tube. Wave guide 41 is enclosed at any point by two adjacent turns of the conductive metallic strip 42 and by the metallic surface of enclosing cylinder 31. The innermost wall of the helical wave guide 41, lying between adjacent turns of helical edge 43, is open insofar as radiation of electromagnetic fields is concerned. Accordingly, there may be a transfer of energy between an electron beam traveling axially through the tube and electromagnetic traveling waves progressing axially within the helical guide 41 within the exciter section 32 of the apparatus illustrated.

35 The end turns 45 and 46 of the conductive strip 42 are circular rather than helical and hence provide substantially planar terminations. As a consequence of this construction, the spaces between the last helical turns of strip 42 and the planar ends 45 and 46 uniformly diminish in cross section.

40 By means of lead 50, which connects the end turn 45 of strip 42 to the accelerating electrode 26, all metallic components within cylinder 31 are maintained at the static potential of anode 26.

45 In the aforementioned co-pending application Serial No. 788,724, it was clearly demonstrated that a beam traveling wave tube utilizing a single helical wave guide of substantially uniform pitch could be caused to oscillate by suitable feedback from output to input ends thereof. It was disclosed that one manner in which such feedback

could be obtained was by mismatching terminations of the wave guide. This basic oscillator principle is used in the apparatus of Figure 1 in the present application.

For successful operation of the exciter section 32, as an oscillator, the average velocity of electrons entering through the opening 51 in end turn 45 must be somewhat greater than the axial component of velocity of an electromagnetic traveling wave passing through the helical wave guide 41. The electron beam entering this wave guide region where feedback is provided in the manner described will cause the exciting section 32 to oscillate at a frequency which is determined by the physical configuration of the wave guide structure and the average electron beam velocity. Since a transfer of energy is required from the electron beam to the traveling wave in order to sustain oscillation, the average velocity of electrons will be somewhat lowered in their transit through the exciting section 32 of the tube illustrated in Figure 1.

Self-oscillation of this tube section may of course be accomplished by inserting suitable couplers extending to the input and output ends of the helical wave guide structure shown, and coupling a portion of the output signal energy back to the input end. This feedback connection may include a frequency sensitive element such as a resonant cavity in order that the exciting section 32 oscillate at a fixed frequency. In the present illustration, the over-all structure is simplified by utilizing the principle of self-oscillation as a result of mis-matched terminations.

A suitable direct current component return path as required by the oscillator section 32 is assured by annular conductive insert 69 having reduced diameter opening 70 formed therein. This reduced section intercepts a portion of the electron stream, and by lead 50 these electrons are returned to the power source. Thus, the number of particles passing through opening 70 for subsequent acceleration is less than the total number of particles in the beam.

The accelerating region 33 of the electron tube illustrated in Figure 1 is constituted essentially of a helical wave guide structure in most respects similar to that previously described in connection with the exciting section 32. Thus, as illustrated in the drawing, the accelerating section 33 consists of a helical wave guide 52 formed by a helically wound thin conductive strip 53 (similar to strip 42) extending from the planar end wall 46 of the exciting section 32 to the end of the conductive cylinder 31 adjacent the collector electrode 27. The helically wound strip 53 in contact with conductive cylinder 31 defines the helical wave guide passage 52 which progresses axially of the tube toward collector electrode 27 and which encloses the co-axial electron beam path 28.

The helical wave guide structure constituting the accelerating region 33 differs from the helical wave guide 41 which forms the oscillator section 32 in that the helical pitch of the metallic strip 53 gradually increases in its progression toward collector electrode 27. At its extreme left turn 55 the pitch of the accelerating section 33 is substantially equal to the pitch of the helical wave guide structure constituting the exciter section 32. At its extreme right hand turn 56, the pitch of the accelerating section 33 is considerably greater than the pitch at its input end 55.

In order to preclude signal reflections from the right end of the accelerating wave guide 52, a uniformly tapered helical dissipative block 61 is

provided within the last turn of the wave guide 52 formed by metallic strip 53. The block 61 is preferably formed of a material capable of effectively dissipating microwave energy. Signal reflections from the left end of the accelerating structure 33 have been observed to be substantially unimportant in effect, and accordingly, this end of the accelerating structure 33 is merely abutted against the end turn 46 of the exciter wave guide structure.

The helical wave guide 41 within the exciter region 32, and the wave guide 52 within accelerating region 33 are electromagnetically coupled by a coupling element 65 extending through a perforation 66 in the abutting end walls of the helical strips 42 and 53. The coupling element 65 is a short length of conductor formed to provide two loops 67 and 68 which extend into the final turn and the initial turn of the exciting and accelerating helical wave guides, respectively. In this manner, high frequency wave energy which is generated by the oscillator section 32 is coupled into the accelerating section 33 for purposes to be described in greater detail below.

In order to maintain electrons traversing axis 28 between accelerating electrode 26 and collector electrode 27 in a sharply defined axial beam, means are provided for establishing a substantially uniform and unvarying axial magnetic field. As illustrated in Figure 1, this is accomplished by means of a multi-layer solenoid type coil 71, coaxial with tube 11 and wound upon an insulating cylindrical coil form 72 suitably secured over the outer surface of cylinder 11, and extending axially over the region between the accelerating electrode 26 and the collector electrode 27. Coil 71 is preferably energized from a suitable direct current source (not shown in the drawings). In accordance with well understood principles, an electron which tends to travel a path divergent from the axis 28 of the tube and hence angularly of the field established by the coil 71 will be urged back to axis 28 as a consequence of its interaction with the axial magnetic field.

The operation of the electron accelerator illustrated in Figure 1 will now be discussed in detail, and it will be assumed that all electrodes are suitably energized, together with coil 71, and that exciter section 32 is operative as an oscillator developing high frequency wave energy.

Electrons entering the accelerating region 33 after axially traversing the oscillator section 32, will have an average axial velocity substantially equal to the axial component of velocity of the high frequency traveling wave generated within the exciter section 32. As a result of the extraction of energy from the electron beam by the traveling wave within the oscillator section 32, the average velocity of electrons entering the accelerating section 33 will be somewhat less than the average velocity of electrons leaving the accelerating electrode 26 of the electron gun 20.

High frequency electromagnetic wave energy generated in exciter section 32 and coupled to the helical accelerating wave guide 52 by means of coupling element 65 causes an electromagnetic wave to travel helically within accelerating wave guide 52 at substantially the speed of light, toward the tapered dissipating block 61. Evidently, the axial component of velocity of this last-mentioned traveling wave at any point within wave guide 52 is dependent upon the pitch of the helical wave guide 52 at that point. As previously mentioned, the initial pitch of the accelerating wave guide is preferably substantially

equal to the pitch of the exciter section wave guide 41 and accordingly, electrons entering the accelerating region 33 will be in substantial synchronism with the traveling wave axially progressing therethrough. In traversing the accelerating region 33, electron bunches within the beam remain synchronized with the axial progression of positive potential regions of the traveling wave electric fields extending inwardly toward the electron beam path. Although not thus illustrated, the accelerating wave guide 52 may be formed so that a number of turns thereof at the left end abutting the exciter section 32 are of a pitch equal to that of exciter wave guide 41. This construction will be of aid in ensuring synchronism between the electron beam and traveling wave movements.

As a result of the uniform increase in pitch of the accelerating wave guide 33, the axial component of velocity of the traveling wave within the wave guide 52 gradually increases from the initial velocity at coupling loop 68. This progressive increase in axial wave velocity correspondingly progressively increases the axial velocity of the electron beam bunches synchronized with the movement of the traveling wave and as a consequence, the electrons emerging from the right-hand end of the accelerating region 33 have an average axial velocity considerably in excess of the velocity of these electrons as they entered the accelerating region 33. These high velocity electrons impinge upon collector electrode 27, in turn connected to a suitable load (not shown). Although the electrons emerging from the accelerating region 33 strike collector anode 27 in bunches, a comparatively constant potential may be maintained at electrode 27 by means of a suitable load capacitor 75 connected between collector electrode 27 and a reference potential, such as ground.

The increase in energy represented by the increase in average electron velocity of course is derived from the traveling wave. Thus oscillator section 32 must be of sufficient power to provide the required energy.

It will be noted that if electrons entering the accelerating region 33 are traveling axially at a speed approximately one-tenth that of light, and that if the pitch of the accelerating helical wave guide 52 is at its output end twice the pitch at its input end, then electrons will strike collector electrode 27 at a velocity approximately two-tenths the velocity of light. From consideration of the aforementioned square root relationship between electron velocity and accelerating potential, it is apparent that doubling the electron velocity in the apparatus of Figure 1, corresponds to that velocity change which would be produced by an increase in potential of substantially four times that applied. Thus, by doubling the velocity of electrons in the accelerating region 33 of Figure 1, 10,000 volt electrons electrostatically accelerated may be further accelerated to a velocity corresponding to that ordinarily obtained by an accelerating potential of 40,000 volts. It will be noted, however, that 40,000 volts need not be applied to the structure to produce these electrons.

Clearly, the high intensity electrons obtained at the output of the accelerator, shown in Figure 1, need not be impinged upon a collector electrode. Instead, an X-ray anode may be substituted, or a test specimen for electron bombardment. These and other applications of high intensity beams are well known.

Although the electron tube of Figure 1 has been described as an accelerator incorporating a beam traveling wave exciting section, it is apparent that external excitation may instead be provided. Thus, an accelerator tube may be similarly constructed with the exception that the exciter region 32 is omitted and that coupling means (not shown) are provided for exciting the accelerating helical wave guide 52 with electromagnetic wave energy of suitable frequency and energy level. Also, one of the other known electron beam oscillator type electron tubes, as for example, the so-called McNally tube, may be substituted for the beam traveling wave oscillator section 32.

The general application of a helical wave guide particle accelerator to a cathode ray tube structure having otherwise conventional characteristics is illustrated in Figure 2, and reference is now made thereto. The cathode ray tube 100 is in the conventional manner formed of a glass or other suitable evacuated envelope 101, having a flared portion, the face 102 of which is interiorly coated with a phosphor 103 of conventional composition.

The neck 104 of the cathode ray tube 100 encloses a helical wave guide accelerating structure 105 which, in all respects, is identical to the metallic cylinder 31 and the enclosed helical guides illustrated in Figure 1. In view of this identity in structure, no further description of the features of accelerating system 105 is considered necessary at this point.

Also enclosed within the neck 104 of the cathode ray tube 100 is an electron gun 20 having the electrodes of the electron gun 20 of Figure 1.

The outer surface of the neck 104 of the cathode ray tube 100 is fitted with a coil form 72 housing a coil 71 (as in Figure 1) which serves to maintain electrons generated by electron gun 20 in a narrow, axial beam 108 in their travel through the accelerating structure 105 within the tube neck.

For the cathode ray tube illustrated in Figure 2, the electron gun 20 may be of low-voltage design, although a high intensity spot 110 is desired upon the fluorescent screen 103. Acceleration of the electron beam to the desired high intensity level after leaving the electron gun 20 is accomplished by the helical wave guide accelerating system 105, operating in the manner already fully disclosed above in discussion of the apparatus illustrated in Figure 1. Due to the gradual increase in pitch of the accelerating wave guide within structure 105, electrons in beam 108 strike fluorescent screen 103 at a velocity far in excess of the velocity imparted thereto by electron gun 20. The need for impractically high potentials is thus obviated.

As the helical accelerating structure 105 contains a self-excited oscillator section, no high frequency signal need be coupled into the cathode ray tube from an external oscillation generator.

An aquadag or other suitable conductive ring 111 is provided within the cathode ray tube in the region of the fluorescent screen 103. An external terminal 112 is provided for applying a suitable direct potential to this electrode. Magnetic deflection coils 115 are provided for the purpose of deflecting the electron beam 108 in a suitable manner in accordance with the usage of the tube.

Although the cathode ray tube electron beam accelerating means 105 has been illustrated in

Figure 2 as identical to that illustrated in Figure 1, it will be evident that various modifications may be made without in any manner altering the advantages obtained by use of high frequency helical wave guide accelerating means. For example, it is possible to excite the helical accelerating section 105 from an external source of high-frequency energy, and thus omit the exciting section from the tube. This is economical of space within the cathode ray tube 100.

The electron accelerating system illustrated in Figure 1 may be applied to various electronic apparatus other than the cathode ray tube structure illustrated in Figure 2. This particle accelerating system may be employed wherever high velocity electrons are desired and wherever it is undesirable to generate and maintain high direct potentials required for direct acceleration.

The operating principles of this tube need not, of course, be confined to negative particles (electrons). Rather, this invention may be applied to accelerate charged particles of any polarity. Thus, since various modifications and extensions of the principles of the present invention will now become apparent to those skilled in the art, it is preferred that this invention be limited not by the specific embodiments herein illustrated and described but by the spirit and scope of the appended claims.

I claim:

1. A particle accelerator comprising a particle gun for generating a particle beam, a helical wave guide, means for directing said particle beam axially of said helical wave guide, means for coupling high frequency wave energy into said helical wave guide, said helical wave guide having a pitch providing an axial velocity of the traveling wave therein at successive coupling points slightly greater than the velocity of the electron beam at corresponding coupling positions along the beam path due to the axial velocity of the beam particles and being of progressively increasing pitch in the direction of particle movement in said beam.

2. An electron accelerator comprising, within an evacuated envelope, an electron gun for generating an electron beam, means for guiding said beam axially of said envelope, a helically formed conductive member surrounding the path of said electron beam, said member having a pitch to provide an axial velocity of the traveling wave from one point in the wave guide to a corresponding point in the next adjacent convolution of the wave guide which is slightly greater than the velocity of the electrons from a point in the beam path adjacent to the first mentioned point of the wave guide to a position in the electron path adjacent to the second mentioned point in the wave guide and having a progressively increasing pitch over a predetermined axial portion thereof, and means for introducing high frequency energy in the region of said conductive strip.

3. An electron accelerator comprising, within an evacuated envelope, an electron gun for generating an electron beam, said electron beam being directed axially of said envelope, a cylindrical hollow conductor co-axial with said envelope, a conductive strip helically formed in edgewise contacting relation with the inner surface of said cylinder, the radial dimension of said strip being less than the inner radius of said cylinder, whereby said cylinder and strip define a helical wave guide progressing axially of said envelope and having an open inner wall, 75

the path of travel of said electron beam being axial through said helical wave guide whereby an electromagnetic wave flowing within said guide is adapted for energy interchange with said electron beam, means for precluding wave reflections at the terminations of said helical wave guide, said helical strip being formed with a gradually increasing pitch, the pitch at successive points providing an axial component of the electromagnetic wave which is greater than the axial velocity of the adjacent electron beam in the direction of electron travel, and means for energizing said helical wave guide with high frequency energy.

4. An electron accelerator comprising, within an evacuated envelope, an electron gun for generating an electron beam, said electron beam being directed axially of said envelope, a cylindrical hollow conductor co-axial with said envelope, a conductive strip helically formed in edgewise contacting relation with the inner surface of said cylinder, the radial dimension of said strip being less than the inner radius of said cylinder, whereby said cylinder and strip define a helical wave guide progressing axially of said envelope and having an open inner wall, the path of travel of said electron beam being axial through said helical wave guide whereby an electromagnetic wave flowing within said guide is adapted for energy interchange with said electron beam, means for precluding wave reflections at the terminations of said helical wave guide, said helical strip being formed with a gradually increasing pitch, the pitch at successive points providing an axial component of the electromagnetic wave which is greater than the axial velocity of the adjacent electron beam in the direction of electron travel, and means for energizing said helical wave guide with high frequency energy, said last mentioned means comprising a high frequency beam traveling wave oscillator operative from said electron beam and disposed axially between said electron gun and said helical wave guide.

5. An electron accelerator comprising, within an evacuated envelope, an electron gun for generating an electron beam, said electron beam being directed axially of said envelope, a cylindrical hollow conductor co-axial with said envelope, a conductive strip helically formed in edgewise contacting relation with the inner surface of said cylinder, the radial dimension of said strip being less than the inner radius of said cylinder, whereby said cylinder and strip define a helical wave guide progressing axially of said envelope and having an open inner wall, the path of travel of said electron beam being axial through said helical wave guide whereby an electromagnetic wave flowing within said guide is adapted for energy interchange with said electron beam, means for precluding wave reflections at the terminations of said helical wave guide, said helical strip being formed with a gradually increasing pitch, the pitch at successive points providing an axial component of the electromagnetic wave which is greater than the axial velocity of the adjacent electron beam in the direction of electron travel, and means for energizing said helical wave guide with high frequency energy, said last mentioned means comprising a high frequency beam traveling wave oscillator operative from said electron beam and disposed axially between said electron gun and said helical wave guide, wave coupling means extending between said oscillator and said heli-

cal wave guide, and means between said oscillator and helical wave guide for intercepting a portion of said electron beam.

6. In an electrical discharge device, an electron emitter for generating a stream of electrons along an axial path of said discharge device, an accelerator for accelerating the electron stream, a collector electrode for receiving said electron stream, a first helical conductor encircling a first portion of said electron stream path, said conductor comprising a helical wave guide of thin highly conductive material, the helix being of a substantially uniform pitch and progressing axially of the electron path and in coupling relation therewith for effecting transfer of energy between an electron stream in said path and an electromagnetic travelling wave progressing axially within said helical guide, the pitch of said wave guide and the acceleration given the electrons in the electron stream providing an average velocity of the electrons in the electron path somewhat greater than the axial component of velocity of the electromagnetic traveling wave passing through the helical wave guide, the electron beam in said path exciting said wave guide to oscillate at a frequency which is determined by the physical configuration of the wave guide structure and the average electron beam velocity, a conductive strip terminating said wave guide and encircling said electron stream path and having an opening at its center which is of a smaller diameter than the diameter of said electron stream for intercepting a portion of said electron stream, an electrical connection from said wave guide to said accelerator for returning the intercepted electrons to said electron source, a second helical conductor axially juxtaposed with the first helical conductor and encircling a second portion of said electron stream path and comprising a helical wave guide of thin highly conductive material and progressing axially of said stream and in a coupling relation therewith and extending from the terminating strip of said first helical wave guide and toward the opposite end of said discharge device, the pitch of said wave guide being substantially equal to the pitch of the first helical wave guide and progressively increasing in pitch as it progresses toward the opposite end of said wave guide, a coupling element between said first and second wave guides for coupling said wave guides to each other to transfer the high frequency energy generated in said first wave guide to said second wave guide, the pitch of said second wave guide at its abutting position with said first wave guide and the speed of the electrons of reduced speed due to the transfer of energy from said electron stream to said first wave guide being such that the axial component of velocity of the traveling wave in said second wave guide is in substantial synchronism with the speed of the electrons in the path encircled by said second wave guide at the junction with said first wave guide, and the electron stream being accelerated by the axially accelerating wave traveling in said second wave guide to remain in synchronism with the axial progression of the traveling electromagnetic wave in said second wave guide, and a solenoid coil co-axial with said tube and secured thereto and extending axially from said accelerator electrode to said collector electrode and being energizable for sharply defining the axial beam.

7. In an electrical discharge device, an electron emitter for generating a stream of elec-

trons along an axial path of said discharge device, an accelerator for accelerating the electron stream, a collector electrode for receiving said electron stream, a first helical conductor encircling a first portion of said electron stream path, said conductor comprising a helical wave guide of thin highly conductive material, the helix being of a substantially uniform pitch and progressing axially of the electron path and in coupling relation therewith for effecting transfer of energy between an electron stream in said path and an electromagnetic traveling wave progressing axially within said helical guide, the pitch of said wave guide and the acceleration given the electrons in the electron stream providing an average velocity of the electrons in the electron path somewhat greater than the axial component of velocity of the electromagnetic traveling wave passing through the helical wave guide, the electron beam in said path exciting said wave guide to oscillate at a frequency which is determined by the physical configuration of the wave guide structure and the average electron beam velocity, a conductive strip terminating said wave guide and encircling said electron stream path and having an opening at its center which is of a smaller diameter than the diameter of said electron stream for intercepting a portion of said electron stream, an electrical connection from said wave guide to said accelerator for returning the intercepted electrons to said electron source, a second helical conductor axially juxtaposed with the first helical conductor and encircling a second portion of said electron stream path and comprising a helical wave guide of thin highly conductive material and progressing axially of said stream and in a coupling relation therewith and extending from the terminating strip of said first helical wave guide and toward the opposite end of said discharge device, the pitch of said wave guide being substantially equal to the pitch of the first helical wave guide and progressively increasing in pitch as it progresses toward the opposite end of said wave guide, a coupling element between said first and second wave guides for coupling said wave guides to each other to transfer the high frequency energy generated in said first wave guide to said second wave guide, the pitch of said second wave guide at its abutting position with said first wave guide and the speed of the electrons of reduced speed due to the transfer of energy from said electron stream to said first wave guide being such that the axial component of velocity of the traveling wave in said second wave guide is in substantial synchronism with the speed of the electrons in the path encircled by said second wave guide at the junction with said first wave guide, and the electron stream being accelerated by the axially accelerating wave traveling in said second wave guide to remain in synchronism with the axial progression of the traveling electromagnetic wave in said second wave guide.

8. In an electrical discharge device, an electron emitter for generating a stream of electrons along an axial path of said discharge device, an accelerator for accelerating the electron stream, a collector electrode for receiving said electron stream, a first helical conductor encircling said electron stream path and in coupling relation therewith, the helix being of a substantially uniform pitch and progressing axially of the electron path and in coupling relation therewith for effecting transfer of energy

between an electron stream in said path and an electromagnetic travelling wave progressing axially within said helical guide, the pitch of said wave guide and the acceleration given the electrons in the electron stream providing an average velocity of the electrons in the electron path somewhat greater than the axial component of velocity of the electromagnetic travelling wave passing through the helical wave guide, the electron beam in said path exciting said wave guide to oscillate at a frequency which is determined by the physical configuration of the wave guide structure and the average electron beam velocity, a second helical conductor in axial relation with the first conductor and encircling said electron stream path and progressing axially of said stream and in a coupling relation therewith and extending from the terminating strip of said first helical wave guide and toward the opposite end of said discharge device, the helical pitch of said second wave guide gradually increasing as it progresses toward said opposite end of said discharge device, the pitch of said wave guide being substantially equal to the pitch of the first helical wave guide and progressively increasing in pitch as it progresses toward the opposite end of said wave guide and a coupling element for coupling said first and second wave guides to transfer the high frequency energy generated in said first wave guide to said second wave guide, the pitch of said second wave guide at its abutting position with said first wave guide and the speed of the electrons of reduced speed due to the transfer of energy from said electron stream to said first wave guide being such that the axial component of velocity of the travelling wave in said second wave guide is in substantial synchronism with the speed of the electrons in the path encircled by said second wave guide at the junction with said first wave guide, and the electron stream being accelerated by the wave travelling in said second wave guide to remain in synchronism with the axial progression of the travelling electromagnetic wave in said second wave guide.

9. In an electrical discharge device, an electron emitter for generating a stream of electrons along an axial path of said discharge device, an accelerator for accelerating the electron stream, a collector electrode for receiving said electron stream, and a helical conductor encircling said electron stream path and of thin highly conductive material and progressing axially of said stream and in a coupling relation with said electron path, the helical pitch of said conductor gradually increasing as it progresses along said axial path toward said collector electrode and the speed of the electrons in said electron stream and the pitch of said conductor at the electron emitting end being such that the axial component of velocity of the travelling wave in said conductor is greater than the axial velocity of the electrons at the corresponding position, and the electron stream being accelerated by the wave travelling in said conductor to remain in synchronism with the axial progression of the travelling electromagnetic wave in said conductor.

10. In an electrical discharge device, an electron emitter for generating a stream of electrons along an axial path of said discharge device, an accelerator for accelerating the electron stream, a collector electrode for receiving said electron stream, and a helical conductor encircling said electron stream path and comprising a helical wave guide of thin highly conductive material

and progressing axially of said stream and in a coupling relation with said electron path, the helical pitch of said wave guide gradually increasing as it progresses along said axial path toward said collector electrode, the speed of the electrons in said electron stream and the pitch of said wave guide at the electron emitting end being such that the axial component of velocity of the travelling wave in said wave guide is greater than the axial velocity of the electrons at the corresponding position, and the electron stream being accelerated by the wave travelling in said wave guide to remain in synchronism with the axial progression of the travelling electromagnetic wave in said wave guide.

11. In an electrical discharge device, an electron emitter for generating a stream of electrons along an axial path of said discharge device, an accelerator for accelerating the electron stream, a collector electrode for receiving said electron stream, and a helical conductor encircling said electron stream path and comprising a helical wave guide of thin highly conductive material and progressing axially of said stream and in a coupling relation with said electron path, the helical pitch of said wave guide gradually increasing as it progresses along said axial path toward said collector electrode, the speed of the electrons in said electron stream and the pitch of said wave guide at the electron emitting end being such that the axial component of velocity of the travelling wave in said wave guide is greater than the axial velocity of the electrons at the corresponding position, and the electron stream being accelerated by the wave travelling in said wave guide to remain in synchronism with the axial progression of the travelling electromagnetic wave in said wave guide, and a solenoid coil co-axial with said tube and secured thereto and extending axially from said accelerator electrode to said collector electrode and being energizable for sharply defining the axial beam.

12. In an electrical discharge device, an electron emitter for generating a stream of electrons along an axial path of said discharge device, a collector electrode for receiving said electron stream, and a helical conductor encircling said electron stream path and comprising a helical wave guide of thin highly conductive material and progressing axially of said stream and in a coupling relation with said electron path, the helical pitch of said conductor gradually increasing as it progresses along said axial path toward said collector electrode, the speed of the electrons in said electron stream and the pitch of said conductor at the electron emitting end being such that the axial component of velocity of the traveling wave in said conductor is greater than the axial velocity of the electrons at the corresponding position, and the electron stream being accelerated by the wave traveling in said conductor to remain in synchronism with the axial progression of the traveling electro-magnetic wave in said conductor.

13. In an electrical discharge device, an electron emitter for generating a stream of electrons, a helical wave conductor adjacent said stream and in coupling relation thereto, said helical conductor having an increasing pitch in the direction in which said electrons move for acting on said electron stream to increase the electron velocity in accordance with the increasing pitch of said conductor, and the pitch of the wave conductor at any point being such that the axial velocity of the electromagnetic wave is greater than the

17

velocity of the electrons at the corresponding position.
